ATTORNEY.

UNITED STATES PATENT OFFICE

CHARLES A. MACREADY, OF SPRINGFIELD, MASSACHUSETTS

CIGARETTE HOLDER

Application filed May 20, 1927. Serial No. 192,885.

This invention relates to improvements in cigarette holders. An object of my invention is to provide a holder for a lighted cigarette which will prevent the same from being entirely consumed. It is a well known fact that a lighted cigarette, if placed in a horizontal or inclined position will be entirely consumed. It also produces a large volume of offensive smoke during the time it is left in this position. A piece of furniture on which the lighted cigarette is placed, is often burned in spots, and occasionally fires are started. The present invention is designed to overcome these objections. The holder is so constructed that the heat from the lighted cigarette is radiated permitting it to burn slowly for a few minutes and then to become extinguished, if it is not given a puff or two by the user, as will be fully described.

Broadly it comprises a substantially cylindrical shaped member in which member the lighted end of a cigarette is placed which is in a vertical position. A stop or plate is located below and spaced a short distance from the lower end of the cylindrical shaped member and on which plate the lighted end rests. The distance of this plate below the lower end of the cylindrical shaped member will determine how much of the length of the cigarette will be consumed before it is extinguished. Means are provided for attaching the holder to an ash tray and which is so constructed to permit the holder to be easily removed.

Referring to the drawings:

Fig. 1 is a plan view of the holder.
Fig. 2 is a side elevation.

Fig. 3 is a plan view of an ash tray showing the holder located thereon, with a cigarette inserted in the holder.

Fig. 4 is a vertical sectional view on the line 4—4 of Fig. 3 illustrating a lighted cigarette in the holder and resting on the stop and

Fig. 5 is a sectional elevational view on the line 5—5 of Fig. 4 showing the holder attached to the shell on which a cigar is usually placed.

Referring to the drawings in detail:

1 designates an ash tray of the usual saucer shape; 2 is the usual shelf portion on which

a cigar or cigarette is placed. 3 designates the cylindrical part of the holder which is formed from very thin metal, as brass. 4 designates a slit that extends the length of the part 3. That portion of the cylindrical part 3 on one side of the slit 4 is extended downward as shown at 5, to form the stop or foot piece 5'. The cylinder part 3, as shown, is open at its lower end. The cylindrical part 3 is also formed with an integral portion 6 having the integral offset portions 7 and 8 which are designed for attaching the holder to the U shaped shelf 2. This is accomplished by bending these offset portions downward, as shown clearly in Fig. 5, in order that they may snugly and frictionally engage the U shaped shelf to permit the holder to be readily attached to and detached from the shelf by sliding it on and off.

The upper end of the cylindrical part 3 is preferably made slightly cone-shaped or flaring as indicated at 9 to permit the ready insertion of a cigarette which is indicated at 10. The lighted end is indicated at 11.

The operation of the holder may be described as follows: When a lighted cigarette is placed in the cylindrical part 3 with its lighted end 11 resting on the offset or foot piece 5', the cigarette will continue to burn slowly until the lighted part reaches the lower end or edge 3' when it will go out, due to the inability of obtaining sufficient air or oxygen. Slow burning of that portion of the cigarette which extends from the upper edge of the piece 6 to the lower edge 3' is due to the thin metal of the holder which will radiate a large portion of the heat that is emitted from the lighted end, therefore preventing this part of the cigarette from being rapidly consumed. This is the important feature of my improvement as it prevents large volumes of smoke from being given off, and further it permits the user to lay his cigarette one side for a few minutes, two or three, without its being entirely consumed. He may at his leisure take a draw or two and then replace it again in the holder for further use. There is also no danger of the cigarette burning or setting fire to anything.

The article is light in weight, inexpensive,

attractive in appearance and one that serves a useful end for the purpose intended.

It is to be understood that I do not limit myself to the exact features and structure herein shown as other and analogous forms 5 are clearly possible but all embodying the feature of a stop or foot piece, a supporting part and a heat radiating part which embodies the principle described.

10 What I claim is:

1. A device for supporting a lighted cigarette, comprising a barrel shaped holder part open at its lower end, a member forming a portion of the holder part and located at and 15 spaced below the open lower end of the holder part on which member the lighted end of a cigarette rests, and means forming a part of the holder for supporting the same on the U-shaped shelf of an ash tray, as described.

20 2. A device for the purpose described, comprising a holder part of thin material and a foot piece attached to the holder and spaced a distance from the lower end of the holder to determine the length or portion 25 that a lighted cigarette will consume before it is extinguished.

3. A detachable cigarette holder member 30 for ash trays that are formed with a U-shaped shelf, said member having an arm for attachment to the U-shaped shelf of the tray and the arm having bendable wing portions for removably supporting the said holder on the U-shaped shelf of the ash tray, means on the holder member for supporting 35 the lighted end of a cigarette, when inserted in the said holder and for lowering its normal rate of combustion, whereby the cigarette will be gradually extinguished after a definite or small length of the cigarette has 40 been consumed, as described.
